F. R. CRANE, JR

OIL BURNING SYSTEM

Filed Jan. 27, 1922

Fig. 1.

Patented July 8, 1924.

1,500,574

UNITED STATES PATENT OFFICE.

FRANK RYERSON CRANE, JR., OF CHICAGO, ILLINOIS, ASSIGNOR TO RYERSON CRANE, INC., OF CHICAGO, ILLINOIS, A CORPORATION OF ILLINOIS.

OIL-BURNING SYSTEM.

Application filed January 27, 1922. Serial No. 532,140.

To all whom it may concern:

Be it known that I, FRANK R. CRANE, Jr., a citizen of the United States, residing at Chicago, in the county of Cook and State of Illinois, have invented certain new and useful Improvements in Oil-Burning Systems, of which the following is a specification.

This invention relates to improvements in oil burning systems.

One of the objects of the invention is to provide an oil burning system in which the oil and the air used therewith to promote combustion thereof, are subjected to uniform equal pressures.

Another object is to provide a system in which a single pump is used by which air pressure is superimposed upon a body of oil contained in a common service reservoir or tank and from which oil and air are independently conducted to an atomizing burner near the point of utilization.

Another object is to subject oil and air in the same tank to pneumatic pressure whereby the body of air will act as a cushion for the oil, that the flow of oil thru the atomizing burner may be more regular, continuous and uniform than when directly moved by a pump.

Another object is the provision of means for filling the service tank from a main reservoir by the use of the motor operating to attenuate the air in the service tank, thereby causing the oil to flow thereinto.

Another object is to cleanse the air used with the oil to promote combustion, by first passing the air through a body of lubricating oil, the oil vapor caused by ebullition of the oil due to the air passing therethru, serving as a lubricant for the air pump.

Other objects and advantages of the invention will hereinafter appear.

In the drawings:—

Fig. 1 is a schematic view of the system in a more incomplex form without the refinements that may be employed therewith and shown more specifically in Fig. 3.

Fig. 2 is a side elevation of the service tank when the motor and rotary pump is mounted thereon.

Fig. 3 is a transverse section taken substantially in a plane with pipe 16 of Fig. 2.

In all the views the same reference characters are employed to indicate similar parts.

I have shown in this application an atomizing burner and a series of safeguarding heat-responsive and pressure-responsive instrumentalities, which I use in the present system in the performance of their respective functions in a manner to produce substantially their normal respective results, and as these devices are staple articles of trade they will not be specifically described in this specification.

While the system is designed especially for promoting combustion of oil for producing heat to be utilized in existing plants used for domestic purposes, as for residences and the like, it may advantageously be used for any purpose for which the combustion of oil is desirable, and in situations where it is desirable to install systems of this character which will operate by the absence of objectionable noise.

In the particular exemplification I have shown the system associated with a hot air furnace 5 having heat conveying pipes 6 and a pipe 7 for conveying away the waste products of combustion. The fire pot 8 is lined with refractory material 9 against which the flame from the burner 10 impinges. A torch or pilot light 11 is located below the atomizing burner 10 and a gas pipe 12 supplies the fuel to the pilot burner.

14 is the service tank or reservoir to be partially filled with oil 15. A pipe 16 extends to the bottom of the tank 14 and extends from the tank to the atomizing burner 10, thereby carrying the oil 15 to the burner. Another pipe 17 is secured to the top of the tank 14 by suitable means, as at 18, and branches into a pipe 19 which is connected to the pump 20 in Fig. 1 and to a four-way valve 27 in Fig. 3. A pipe 21 conveys air from the tank and from the pump thru the four-way valve to the atomizing burner 10.

The pump 20, which is an air pump, is driven by the electric motor 25 thru a coupling 26. Normally the pipe 17 is connected to the pipe 19 thru the valve 27, and when the pump is rotating it compresses air in the tank 14, and at the same time air is conveyed thru the pipe 19 and the pipe 21 to the burner 10.

The air intake to the pump 20 is thru a tank 28. Tank 28 has a vent hole 29 and contains lubricating oil 30 up to the vent hole. One object of the vent hole is to indi-

cate the level of the oil 30 in the tank. The oil is filled into the tank thru the cap closing filling opening 31. The vent hole 29 is relatively small with respect to the main 5 air intake pipe 32, which is open to the atmosphere, the lower end of which extends nearly to the bottom of the tank 28. A pipe 33 is connected thru the intake pipe 34 and a check valve 35, so that normally, air will 10 be taken into the pump 20 thru self-opening check valve 35 and the tank 28 after passing thru the lubricating oil 30. The passage of the air thru the lubricating oil will produce ebullition of the oil and more or less oil 15 vapor will pass with the air thru pipe 33 into pump 20 and lubricate it. A relatively small quantity of air will also pass into tank 28 thru vent 29 but the major portion will enter thru the pipe 32. The air that 20 passes into the pump thru the pipe 33 and 34 is compressed by the pump and passes out thru the discharge opening into the pipes 19 and 21, thus producing air pressure in the service tank 14 proportional to the resistance 25 interposed by the burner, and also causing the air to pass thru the pipe 21 to the burner 10. A safety valve 36 is located in the pipe 37 to prevent the air pressure from rising 30 too high in the tank 14.

30 A pipe 38 connects the intake of the pump 20 with the pipe 37 which contains a blow off valve 36. When the apparatus shown in Fig. 3 is to be used the pump 20 is set into operation by the motor 25. At 35 this time the valve 27 is turned to connect the intake of the pump with pipe 34 and pipe 39 with pipe 38; air will therefore, pass into the pipe 32 thru the oil contained in the tank 28 and thru the pipe 33, check valve 35, 40 into the pipe 34, and from thence thru the four-way valve 27 into the pump. Air under pressure will pass from the pump to the pipe 19 into the upper part of the supply tank 14 thru pipe 39, valve 27 and pipe 38, 45 and air will also pass thru the pipe 21 to the burner 10, which will atomize the oil coming to the burner thru pipe 16. Now, when it is desirable to partially fill the tank 14 with oil 15 from an outside reservoir, which may 50 be located at a lower level than the service tank 14, the valve 27 is rotated about 90 degrees; so that communication between the pipes 17 and 21 is closed and communication between pipes 19 and 34 is open. Air 55 will now be drawn from the tank 14 thru the pipes 17, 38, valve 27, and create more or less of a vacuum therein; therefore oil will enter thru the supply pipe 41 from the supply reservoir when the valve 42 is open. 60 The air will be exhausted from the pump thru the burner 10, as at this time no oil will pass into the burner because of the fact of the high attenuation of air in the tank 14.

65 In Fig. 1 I have shown a hand operated

pump 43 operated by the handle 44 for pumping oil into the tank 14 thru the pipe 41 from the storage tank or supply reservoir not shown.

The means for controlling the apparatus, 70 that is to say, for stopping the rotation of the motor 25, when there is any serious derangement with the devices for feeding fuel to the furnace, standard safe-guarding devices may be used in the manner herein 75 disclosed.

The double pole switch 46 is connected between the service wires 47' and 48' and the mains 47 and 48. The wire 47' is connected to the motor 25 thru a switch 50 which is controlled by an electromagnet 51. When the switch is closed the electric motor will operate, and when it is open the motor will stop. A heat-responsive device 52 is contained in the circuit 53 and so also is a heat-responsive device 54 which is affected by the pilot burner 11 associated with the spraying burner 10. The wires 55 and 56 connect the transformer 57 with the service wires 47' and 48', and the secondary wires 58 80 and 59 are those in which the safe-guarding automatically operating devices are contained.

A pipe 60 connects the casing 61 with the upper part of tank 14. A diaphragm 62 extends across the end of the pipe 60, having a packing disk 63 to close the pipe. The edge of the diaphragm is clamped to the edge of the casing by the cap 64. Inside cap 64 is a coiled spring 65 bearing on the 100 diaphragm and adjustable by a threaded stem 66 when the handle 67 is turned. This provides a safety device to prevent pressure from rising dangerously high in tank 14. This may be used supplemental to the pressure valve 36 or without it.

While I have herein shown a single embodiment of my device for the purpose of clear disclosure, it will be manifest, to persons skilled in the art, that many changes 110 may be made in the general arrangement and configuration of the parts within the scope of the appended claims.

Having described my invention what I claim as new and desire to secure by Letters Patent is:—

1. A system of the character described comprising an oil spraying burner; a tank containing a liquid fuel; an air pump connected to the tank to pump air into the tank 120 to produce pressure to move a liquid therefrom and to serve as a reservoir of air for the burner; a pipe leading from the bottom of the tank to the burner; another pipe leading from the top of the tank to supply air 125 to the burner and an oil supply pipe connected to the tank in combination with a valve movable to connect the intake of the pump to said tank to exhaust air therefrom to fill the tank with oil when said supply 130

pipe is open and alternatively movable to close said air connection and to connect the intake port of the pump to another source of air supply and to connect the discharge port of the pump to said tank.

2. A system of the character described comprising a spraying burner; a tank for containing liquid fuel; an air pump arranged to pump air into the tank to produce pressure to move the liquid; a pipe leading from the bottom of the tank to the burner

to convey the liquid fuel thereto; another pipe leading from the top of the tank to the burner to convey air under pressure to said burner; another tank connected to the air intake of the pump and a liquid in the last mentioned tank thru which the air passes on its way to the pump. 15

In testimony whereof I hereunto subscribe my name.

FRANK RYERSON CRANE, JR.
